US0D1095686S

(12) **United States Design Patent** (10) **Patent No.:** **US D1,095,686 S**
(45) **Date of Patent:** **** Sep. 30, 2025**

(54) **PUZZLE BOARD**

(71) Applicant: **Zhengmei Zhou**, Puning (CN)

(72) Inventor: **Zhengmei Zhou**, Puning (CN)

(**) Term: **15 Years**

(21) Appl. No.: **29/968,521**

(22) Filed: **Oct. 17, 2024**

Related U.S. Application Data

(63) Continuation-in-part of application No. 29/936,598, filed on Apr. 9, 2024, now Pat. No. Des. 1,053,962.

(57) **CLAIM**

The ornamental design for a puzzle board, as shown and described.

DESCRIPTION

FIG. 1 is a front perspective view of a puzzle board, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view of the puzzle board, in a partially disassembled state; and,

FIG. 10 is another front perspective view of the puzzle board, in a disassembled state.

The broken lines in the drawings illustrate portions of the puzzle board that form no part of the claimed design.

1 Claim, 8 Drawing Sheets
